CARBOY CUSHION

Richard W. Lahey, New Rochelle, N. Y., and Harry A. Kast, Erie, Pa., assignors to American Cyanamid & Chemical Corporation, New York, N. Y., a corporation of Delaware

Application April 19, 1934, Serial No. 721,356

5 Claims. (Cl. 217—52)

The present invention relates to a boxed carboy and to cushioning members used therewith to carry the glass bottle occurring therein and protect the same against breakage during handling and shipping.

The principal object of the invention is to provide a cushioning member or members of cheap material, having long life, and which will have a high capacity of absorbing shocks under all normally occurring temperatures.

The question of cushioning members to be used for boxed carboys has been given considerable thought during the past few years but each manufacturer has arrived at a combination which he believes to be most efficient without, however, there being any standardized uniformity of the various types. At most it can be said that it is common practice today to ship liquid materials in large bottles which are in turn packed in wooden cases with some kind of cushioning means in between the bottle and the casing. Every type of cushioning member on the market today is open to some objection. As a result, the Interstate Commerce Commission, having determined on no standard construction of cushioning member, have devised certain so-called swing tests as a standard of efficiency which all boxed carboys must pass before they will be accepted in interstate trade as a shipping container for certain types of dangerous corrosive liquids.

A study of these devices now in use shows that they are made of almost every conceivable kind of material. For instance, some boxes contain wooden slats between the box and the bottle. Others seat the bottle on blocks of cork either formed from a single integral section or from ground waste material secured together by suitable binders. Other manufacturers use aggregates of cork bound together with such materials as asphalt or other semi-plastic substances.

It has been found through experimentation over a considerable period, that all of these materials are open to objection.

Spring wooden slats are objectionable from the standpoint that their shock absorbing capacity is small, far from uniform, and are subject to contraction and expansion when exposed to moisture.

Cork is objectionable from the standpoint that it has large permanent deformations under pressure. This material is also unsatisfactory in that it does not provide a sufficient cushioning effect and has such quick rebound as to make it entirely undesirable.

Ordinary rubber has been tried without suc-

cess, by reason of the fact that the materials heretofore employed have either been too elastic, not elastic enough, or its age resisting qualities have been so low as to make it entirely unsuitable for this purpose. The usual types of rubber also become unduly hard when brought in contact with acid. In carboys in which acid is stored or shipped, this contact cannot be entirely avoided for when portions of the contents of a bottle are removed, there is always some drip and this quantity runs down the inside of the bottle, contacts with the rubber cushions, with the above detrimental effect.

Particles of cork embedded in asphalt or other semi-plastic materials of this type are objectionable from the standpoint that under extreme weather conditions their capacity to absorb shocks is so modified as to render them useless. For instance, at 0° F. an asphaltic combination becomes so brittle as to lose its ability to absorb shocks, whereas at 100° F. the asphaltic ingredient becomes so soft as to permit definite positive deformation to take place. It is, of course, recognized that temperatures of 0° F. and 100° F. are normal temperatures within the life of a carboy. This material is also objectionable in that in a comparatively short period of time, it loses its tackiness and hence separates from the bottle, and crumbles.

One of the principal problems confronting these applicants therefore was to discover a material and to construct a boxed carboy using the same which would not be open to the above objections. It might be here said that the most difficult problem to overcome was the discovery of a material whose efficiency would be substantially unimpaired through normal changes in temperature and/or humidity.

With the above objects in mind, the invention contemplates a cushioning member and its use in a boxed carboy, of a material which has a high capacity to absorb shocks, slow recoil, age resisting qualities, where those properties remain substantially unchanged at temperatures between 0° F. and 100° F.

Among the materials found most suitable for this purpose are unvulcanized, reclaimed rubber either cast in one piece or formed as a laminated section, and ground cork or other filling material, the individual particles of which are encased in rubber so that the combined material has the above properties. It is understood, of course, that these are merely examples of material found suitable and reference thereto is not to be considered in a limiting sense. The real test as to whether

a material is suitable is to subject a boxed carboy containing cushions thereof, to the standardized I. C. C. swing tests at from 0° F. to 100° F. If they stand a swing test of 55 inches or more without bottle breakage, then they are satisfactory for the purpose.

The invention further consists in the novel arrangement, combination and construction of parts more fully hereinafter described and shown in the accompanying drawing.

In the drawing—

Fig. 1 is a plan view of a carboy constructed according to this invention.

Fig. 2 is a view along the line 2—2 of Fig. 1.

Fig. 3 is a fragmentary elevation along the line 3—3 of Fig. 1.

Referring now with particularity to the drawing, a satisfactory form of carboy box is shown to consist of a bottom 1 and side walls 2 of wood or the like suitably nailed together to form an open box. Triangular corner posts 3 are normally used to give the necessary reinforcement.

It is preferred to mount on the bottom 1, wooden cross pieces 4 and 5, the latter over the former, each being provided with a recess near its extremities to receive a cushioning block 6, which extends beyond the periphery of the bottle.

Similar upright sections 7 are provided with upper and lower cushioning blocks 6. It is preferable that on one side of the box the uprights 7 be secured directly to the corner posts 3 as by nails or the like 8 and that the opposite two uprights remain unconnected to the corner posts. Shims or filler pieces 9 may be provided for insertion between a corner post 3 and an upright 7 to take up any play and to insure a tight fit.

It has been found that the most satisfactory material of which cushioning blocks 6 may be made are unvulcanized, reclaimed rubber. Reclaimed rubber has a distinct status in the art. It is cheap. There is almost an unlimited supply available and it may be readily cast into blocks of the desired shape or size or may be built up from sheets into a laminated structure. Perhaps the cast block is more desirable than the laminated block, due to the fact that there is no tendency for the laminations to separate. These blocks 6 may be set loosely within the recesses made to receive them or they may be secured in place as desired.

The Manufacturing Chemists Association has recently developed a 13 gal. glass bottle for the shipment of certain liquid materials. This is referred to as the Manufacturing Chemists Association standard 13 gal. bottle. There are many characteristics of this bottle which make it desirable from a shipping standpoint, although for the purpose of this invention any type bottle may be used.

Blocks 6 having been designed of a size and shape which will most effectively fill out the space between the bottle and the box and which will have sufficient volume to insure the desired cushioning effect, a bottle is set within the box and upon the four blocks 6, resting on the bottom thereof. The two loose members 7 are then inserted and the desired number of shims 9 added to insure tight packing of the bottle. The usual apertured top is then nailed in place.

Unvulcanized, reclaimed rubber is particularly effective for this purpose in that it has a high capacity to absorb shocks, is elastic, it has a slow rate of recoil which thereby eliminates whip, which immediately follows shock absorption; it has a high degree of age resistance and these properties remain substantially unchanged at temperatures ranging from 0° F. to 100° F. Obviously the same characteristics are present in a composite block made of filler material such as ground cork, where the individual particles are coated with this material, where there is sufficient of this unvulcanized reclaimed rubber to give the necessary cushioning effect.

Another property peculiar to this material is that it has a normally tacky surface. As a result, once the bottle rests upon the blocks at the bottom of the box and the side blocks are wedged in against the bottle, there is a more or less permanent adherence between the bottle and blocks which makes unnecessary any extraneous fastening means. This adherence between the block and the bottle serves the distinct purpose of definitely preventing slippage of the blocks after they have once been put in the proper location and also tends to pull the bottle back to the location which it occupied before shock, thus assisting the recoil from the block on the opposite side.

Obviously this adherent quality may be enhanced by softening the surface of a rubber block with benzene or some other similar salt which will permit a cementing or adhering action to take place.

Actual tests have indicated that unvulcanized reclaimed rubber used as above described with the M. C. A. standard 13 gal. bottle, have withstood the Interstate Commerce Commission swing test of 55 inches at various temperatures ranging from 0° F. to 100° F., showing conclusively that the desirable properties of this material remain substantially unchanged over that range.

We claim:

1. A carboy comprising in combination a box, a frangible bottle therein, homogeneous cushioning members of reclaimed rubber between the bottle and the box, said cushioning members having a high capacity to absorb shocks, slow recoil and high age resisting abilities, all of said properties remaining substantially unchanged at temperatures between 0° F. and 100° F., said carboy being capable of successfully withstanding a swing test according to the I. C. C. shipping container standards of not less than 55 inches.

2. A carboy comprising in combination a box, a frangible bottle therein and homogeneous cushioning members of reclaimed rubber between the bottle and the box.

3. The combination of claim 2 in which the rubber cushions are unvulcanized.

4. The combination of claim 2 in which the cushions are adherent to the bottle.

5. The combination of claim 2 in which the cushions are adherent to the bottle by reason of the tacky nature of the surfaces of said cushions.
